UNITED STATES PATENT OFFICE.

CLIFTON D. PETTIS, OF NEW YORK, N. Y.

BRAKE SHOE.

Application filed September 2, 1922. Serial No. 585,904.

To all whom it may concern:

Be it known that I, CLIFTON D. PETTIS, a citizen of the United States, residing at New York, in the county of New York and State of New York, have invented certain new and useful Improvements in Brake Shoes, of which the following is a specification.

This invention relates to brake shoes and has for its primary object to provide a simple and economical construction which will provide greater durability and strength than devices of a similar character heretofore known.

15 The many other objects and advantages of the invention will be better understood by reference to the following specification when considered in connection with the accompanying drawing, illustrating a selected embodiment, in which—

Fig. 1 is a plan view of the reinforcing shell partially formed;

Fig. 2 is an enlarged perspective view of a portion of the back plate of the shell shown in Fig. 1;

Fig. 3 is a plan view of the completed brake shoe;

Fig. 4 is a transverse section on the line 4—4 of Fig. 3; and

30 Fig. 5 is an enlarged section on the line 5—5 of Fig. 4.

Referring to the drawings the brake shoe is provided with a shell 10 comprising a back 11, side walls 14, and end walls 15, the central portion 12 of the back being of greater thickness than the portions 13 on each side thereof. The side walls 14 and end walls 15 are preferably reticulated and formed integral with the back 11. The shell is preferably formed flat (Fig. 1) and then bent into pan shape prior to the casting of the shoe body thereon. In the forming of the shoe the side and end walls are bent downwardly on substantially the lines 16 and then the end walls are bent inwardly on the line 17 so that the ends 18 substantially abut, as indicated in Fig. 3. Openings 19 are thus formed in the shell through which the metal of the body passes to form the end lugs 20. The portions 22 of the shell along the line of bend are preferably not reticulated.

55 The side walls 14 and the end walls 15 are preferably corrugated transversely and longitudinally, as shown in Figs. 4 and 5. This method of corrugating the walls of the

shell is particularly advantageous. The back plate 11 is provided with slots 25 to admit the attaching ends 26 of the lug 27. The body 30 of the shoe is cast in the usual manner with the shell 10 embedded therein.

My improved shell is simple in construction and may be economically produced. The thickened central portion of the shell very materially strengthens the shoe and the connection of the attaching lug therewith. The corrugating of the side and end walls of the shell transversely and longitudinally is advantageous as it provides a better connection between the shell and the cast body and improves the wearing qualities of the shoe.

I am aware that various changes may be made in the form and arrangement of parts without departing from the spirit of my invention and I reserve the right to make all such as fairly fall within the scope of the following claims.

I claim:—

1. In a brake shoe, a reinforcing back comprising a rolled plate of ductile metal having a relatively thick central portion extending longitudinally thereof and relatively thinner portions on each side thereof.

2. In a brake shoe, a reinforcing back comprising a rolled plate of ductile metal having a relatively thick central portion and relatively thinner portions on each side thereof, parts of said thinner portions being foraminous.

3. In a brake shoe, a reinforcing back comprising a rolled plate of ductile metal having a relatively thick central portion and relatively thinner portions on each side thereof, parts of said thinner portions being reticulated.

4. In a brake shoe, a reinforcing back comprising a rolled plate of ductile metal having a relatively thick central portion and relatively thinner portions on each side thereof, the outer edge portion of said thinner portions being foraminous.

5. In a brake shoe, a reinforcing shell comprising a rolled plate of ductile metal having a relatively thick central portion and relatively thinner portions on each side thereof, the outer portion of each of said thinner portions being bent downwardly to form the side walls of the shell.

6. In a brake shoe, a reinforcing shell comprising a rolled plate of ductile metal having a relatively thick central portion

- and relatively thinner portions on each side thereof, the outer portion of each of said thinner portions being reticulated and bent downwardly to form the side walls of the shell. 35
7. In a brake shoe, a pan shaped reinforcing shell of ductile metal comprising a solid metal back plate of varying thickness and foraminous side and end walls formed integrally with said back plate. 40
8. In a brake shoe, a pan shaped reinforcing shell comprising a plate of ductile metal having a relatively thick central portion and relatively thin side portions, portions of said side portions being bent to form the side and end walls of said shell. 45
9. A brake shoe, comprising a reinforcing back having a relatively thick central portion extending longitudinally thereof and relatively thin side portions, an actuating lug secured to the central portion of said back, and a body cast on said back. 50
10. A brake shoe, comprising a reinforcing back having a relatively thick central portion extending longitudinally thereof and relatively thin side portions, a key lug having attaching members passing through said side portions and projecting beneath the under face of said central portion, and a body cast on said back. 55
11. In a brake shoe, a pan shaped reinforcing shell comprising a plate of ductile metal having the edge portions thereof bent to form the side and end walls of the shell and the end lug openings therein. 60
12. In a brake shoe, a pan shaped reinforcing shell comprising a plate of ductile metal having the edge portions thereof reticulated and bent to form the side and end walls of the shell and the end lug openings therein. 65
13. In a brake shoe, a shell comprising a top, sides, and end walls, the sides being corrugated longitudinally and transversely. 70
14. In a brake shoe, a shell comprising a top, sides and end walls, the sides and end walls being corrugated longitudinally and transversely. 75
15. In a brake shoe, a pan-shaped shell comprising a top, sides and end walls, the sides being corrugated longitudinally and transversely and reticulated. 80
16. In a brake shoe, a shell comprising a top, sides, and end walls, the sides being corrugated longitudinally. 85
17. In a brake shoe, a shell comprising a top, sides, and end walls, the sides and end walls being corrugated transversely. 90
18. In a brake shoe, a shell comprising a top, reticulated sides and end walls, the sides being corrugated longitudinally. 95

CLIFTON D. PETTIS.
